UNITED STATES PATENT OFFICE.

JOHN S. BARNES, OF DETROIT, MICHIGAN, ASSIGNOR TO MAJESTIC WIRE FENCE COMPANY, LIMITED, OF DETROIT, MICHIGAN.

WIRE FENCE.

SPECIFICATION forming part of Letters Patent No. 746,441, dated December 8, 1903.

Application filed August 15, 1903. Serial No. 169,564. (No model.)

To all whom it may concern:

Be it known that I, JOHN S. BARNES, a citizen of the United States, residing at Detroit, county of Wayne, State of Michigan, have invented a certain new and useful Improvement 5 in Wire Fences; and I declare the following to be a full, clear, and exact description of the invention, such as will enable others skilled in the art to which it pertains to make and use the same, reference being had to the accompanying drawings, which form a part of this specification.

My invention relates to an improvement in wire fence shown in the accompanying drawings and more particularly set forth in the following specification and claims.

Figure 1 shows a perspective view of my improved fence with the line-wires removed from the pickets at one or more of the intersecting points to more clearly show the form of the picket. Fig. 2 shows a variation in the form of the picket.

The object of my invention is to produce a wire fence which can be readily and quickly 25 manufactured by a power-loom, the construction being such that the pickets can be easily engaged in the loops of the line-wires while the same are being twisted together.

Heretofore in fences of this character it has 30 been found necessary to stop the loom after the wires have been twisted a predetermined distance from the picket to insert the next picket between the strands forming the line-wires of the fence. To do this, the twisting 35 gears were so controlled that when the machine was stopped to receive the picket the open loops of each of the line-wires were exactly parallel. The picket, with its offset portions already formed, was then manually 40 thrust through the loops from one side of the machine and the loom again started. The twisting of the strands proceeded as before until a point was reached for the insertion of another picket, when the operation just described was repeated. By the peculiar construction 45 of my picket I am able to insert the picket in all of the open loops at one time, and the same can be either automatically fed to the wires as they are twisted together or 50 inserted by hand. In either case much time is saved in the manufacture of the fence over

that just described, and at the same time a very handsome and rigid structure is secured.

Other improvements will appear by further reference to the specification. 55

Referring to the letters of reference shown on the drawings, A A are the twisted strands forming the line-wires of the fence.

B represents the pickets, which may be either of sheet metal or of wire, the point at 60 which they intersect the line-wires being formed with a T-shaped crimp B'. The twisted strands forming the line-wires are looped around the stem b of the T-shaped portion B', the twist given to the line-wires being reversed between pickets, the object being to insure a more rigid and substantial structure. It is obvious that the picket may be either flat between the offset portions B', as shown in Fig. 1 of the drawings, or corrugated or 65 formed with a channel, as shown in Fig. 2, as may be desired.

Having thus described my invention, what I claim is—

1. In a fence, sheet-metal pickets bent to 75 form T-shaped offset portions at the intersection of the line-wires in combination with strands twisted together to form said line-wires, the strands being looped around the neck of the offset portion, substantially as 80 described.

2. In a fence, sheet-metal pickets bent to form a projecting neck at the intersection of the line-wires in combination with strands twisted together to form line-wires, the 85 strands being looped around the neck of the offset portion, substantially as described.

3. In a fence, sheet-metal pickets bent to form T-shaped offset portions at the intersection of the line-wires in combination with 90 strands twisted together to form said line-wires, the strands being looped around the neck of the offset portion and twisted in opposite directions from each picket, substantially as described. 95

In testimony whereof I sign this specification in the presence of two witnesses.

JOHN S. BARNES.
